Primary Examiner — Omeed Agilee*Assistant Examiner* — David Truong(74) *Attorney, Agent, or Firm* — Nitin Kaushik(57) **CLAIM**

The ornamental design for a travel bottle, as shown and described.

DESCRIPTION

FIG. 1 is a top perspective view of a travel bottle, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings depict the boundaries of the enlarged views and form no part of the claimed design.
